UNITED STATES PATENT OFFICE.

NELSON T. SHORTS, OF FERN, PENNSYLVANIA.

STOPCOCK OR VALVE.

1,322,964.

Specification of Letters Patent. Patented Nov. 25, 1919.

Application filed October 30, 1917. Serial No. 199,319.

To all whom it may concern:

Be it known that I, NELSON T. SHORTS, a citizen of the United States, residing at Fern, in the county of Clarion, State of Pennsylvania, have invented a new and useful Stopcock or Valve; and I do hereby declare the following to be a full, clear, and exact description of the invention, such as will enable others skilled in the art to which it appertains to make and use the same.

This invention relates to the art of valves and particularly to an improved stop cock or plug valve.

Heretofore, it has been found that when hammering on the core of the valve to loosen it (it having become so tightened from the lack of frequent use and the need of oil), and owing to the high pressure, the valve or core has become broken. The break is usually at the threaded end of the core, and when this end breaks off, the remaining portion of the valve blows out of its casing with terrific force, thereby making it very dangerous for the person operating the valve, and also causing a great deal of inconvenience. For these reasons and the fact that the valve or core of the old style stopcock is extremely easy to become broken, for the further reason that it is constructed of metal casting, such stop-cocks in a great many instances are condemned, and rejected, when submitting plans for the installation of oil and gasolene plants, and water distributing systems and plants, etc.

Therefore, one of the objects of the invention is to provide an improved stop-cock of the plug type, that will not be condemned by hydraulic engineers, etc.

A further object of the invention is the provision of a stop-cock having an opening in the wall of the casing thereof for the reception of a plug, said opening being designed, when its plug is removed and the valve or core closed, to give vent to the fluid, that may collect in the transverse opening of the plug, thereby preventing freezing of the water or other fluid, which would chill the plug or core so that a sudden jar or twisting of the same will cause it to break.

A further object of the invention is to provide a valve core or plug having an extension cast in the lower end of the core or plug, in order to be engaged by a suitable securing means, to hold the plug or core suitably rotatably in the casing.

A further object of the invention is to

provide an extension for the core or plug constructed of any suitable pliable metal, such as pliable iron or brass or the like, and which extension, should the plug or core become damaged otherwise than disclosed above, may be removed, and cast in another plug or core.

In practical field the details of construction may necessitate alterations falling within the scope of what is claimed.

The invention comprises further features and combination of parts as hereinafter set forth shown in the drawings and claimed.

In the drawings:—

Figure 1 is a view in side elevation of the improved valve constructed in accordance with the invention.

Fig. 2 is a vertical sectional view through the same.

Fig. 3 is a horizontal sectional view on line 3—3 of Fig. 1.

Fig. 4 is a vertical sectional view on line 4—4 of Fig. 1.

Fig. 5 is a detail perspective view of the lower end of the plug or core.

Fig. 6 is a detail plan view of a washer for the lower end of the core or plug.

Referring more especially to the drawings 1 designates the casing of the valve, which 85 may be constructed of any suitable metal, preferably cast iron metal, and may have any suitable configuration or shape, preferably as shown in the drawings. This casing at its opposite ends is provided with 90 passages 2 and 3, either of which may be used as the inlet or outlet passage. However, the outer end of each passage is provided with threads 4, to be engaged by the exterior threads of an adjoining pipe section. Constructed through the casing 1 between the adjacent ends of the passages 2 and 3 and at right angles thereto is a conical chamber 5, for the reception of a tapering valve-plug or core 6, which may be constructed of any suitable metal, preferably 100 cast iron metal. The larger end of the plug or core is provided with a reduced extension 7, preferably rectangular in cross section, to receive any suitable device or conventional 105 form of handle (not shown), whereby the plug or core may be turned, whereby its transverse passage 8 may register with the passages 2 and 3, or disposed at right angles to said passages 2 and 3, to cut off the fluid.

The wall of the casing 1 on one side is provided with an opening 9, the larger portion

10 of which is threaded, for the reception of the threaded plug 11, the outer end of which has an extension 12, preferably rectangular in cross section, to receive a suitable wrench or the like, whereby the threaded plug 11 may be moved, when such is necessary. At all times, preferably during freezing weather and when the plug or core has been turned to dispose its passage at right angles to the passages 2 and 3, said plug 11 is removed, in order to draw off the fluid or water that is collected in the opening or passage 8, thereby preventing such fluid from becoming frozen and consequently causing the valve plug or core to become chilled so that a sudden jar or twisting of the plug will cause it to break, or otherwise become so fractured as to prevent the necessary and proper operation of the valve. The valve plug or core is provided with a reduced threaded separable extension 13, the inner end of which is supplied with a head 14, preferably rectangular in cross section. The plug or core 6 is designed to be constructed by casting the same, and after which its outer conical or tapering surface is designed to be machined, so that the plug or core will closely and rotatably fit the tapering chamber 5. As the core or plug 6 is constructed, the headed end portion of the separable extension 13 is cast on the interior of the tapered end of said plug or core. By means of the head 14, the extension 13 (which may be constructed of any suitable metal, preferably pliable iron or brass) is prevented from revoluble and longitudinal or axial movement. The valve plug or core has an integral reduced extension 15, which extends beyond the valve casing, and engaging said extension 15 is a washer 16, which engages rotatably flat against one end of the valve casing 1, and is held on said extension 15 by the nut 17, which is threaded upon the separable extension 13. The wall of the opening 18 is provided with a flat surface 19, which engages a flat surface 20 of the extension 15, thereby causing the washer 16 to rotate with the valve plug or core 6. Plugs of valves of this type are constructed entirely of cast iron, therefore when they become chilled or receive a sudden jar, particularly from a hammer or other tool they are easily broken. It is common practice for mechanics when a plug valve becomes stuck to tap the same on the head 7, which tapping operation is designed to loosen the plug. However, if the plug is chilled as is generally the case where the same is used in pipe lines out of doors, such hammering action causes the depending threaded integral lug to become what is known as bounced off. By making the depending lug of a metal such as brass or wrought iron, such as shown at 13, which

metal is ductile and is not rendered brittle by excessive low temperatures, the hammering action upon the end 7 of the plug valve will not cause the breaking off of the depending threaded lug, for the reason that in the case of brass or other ductile metal there is a certain amount of stretch.

The invention having been set forth what is claimed as new and useful is:—

1. In a stop-cock or plug valve, a valve casing having a fluid passage and a conical chamber extending at right angles to said passage, a tapering valve plug or core in said chamber, the tapered end of the plug or core having a threaded extension and provided with a transverse passage adapted to register with the fluid passage of said casing, a nut on said threaded extension, said threaded extension being embedded in the lower tapered end of said core or plug and being constructed of a metal having a greater yielding tendency than the core, whereby the extension may stretch and be prevented from becoming broken when chilled incident to shocks of said valve.

2. In a stop-cock or plug valve, a casing having a fluid passage and provided with a tapering chamber at right angles to the said passage, a tapering valve core or plug in the chamber and provided with a passage adapted to register with the fluid passage of the casing, the tapered end of the core or plug having an extension adapted to give or stretch incident to the plug or core receiving shocks when chilled, a nut threaded to said extension to hold the core in its chamber, and a plug closed opening in the wall of the casing, to draw off the fluid that may collect in the space or passage of the core when closed.

3. In a stop-cock or plug valve, a casing having a fluid passage and provided with a tapering chamber at right angles to said passage, a tapering valve core or plug in the chamber and provided with a passage adapted to register with the fluid passage of the casing, said core or plug being constructed of cast iron metal and a brass or wrought iron bolt having its headed end cast in the tapered end of the core or plug, thereby constituting an extension, a nut threaded on said extension to hold the core or plug in said chamber, and a plug closed opening in the wall of the casing to draw off the fluid that may collect in the space or passage of the core when closed.

In testimony whereof I have signed my name to this specification in the presence of two subscribing witnesses.

NELSON T. SHORTS.
